CLAIM

The ornamental design for the LED ceiling light, as shown and described.

DESCRIPTION

FIG. 1 is a perspective view of the LED ceiling light showing my new design;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof; and,

FIG. 7 is a top plan view thereof.

In the drawing views, the broken lines represent unclaimed portions of the LED ceiling light and form no part of the claimed design.
